UNITED STATES PATENT OFFICE.

JAMES L. WITHEY, OF MELROSE, ASSIGNOR TO GORDON McKAY, TRUSTEE
FOR McKAY SEWING MACHINE ASSOCIATION, OF BOSTON, MASS.

MACHINE FOR SEWING BOOTS AND SHOES.

SPECIFICATION forming part of Letters Patent No. 224,063, dated February 3, 1880.

Application filed March 26, 1879.

To all whom it may concern:

Be it known that I, JAMES L. WITHEY, of Melrose, county of Middlesex, State of Massachusetts, have invented an Improvement in 5 Machines for Sewing Boots and Shoes, of which the following description, in connection with the accompanying drawings, is a specification.

This invention relates to improvements in 10 sewing-machines for boot and shoe work where a waxed thread is employed.

My improvement is shown as embodied in connection with the horn of the so-called "McKay machine."

15 Waxed thread in the McKay sole-sewing machines is commonly held upon a large tin spool, it and the thread, when fully wound, weighing about two and one-half pounds.

20 It is a great desideratum, in uniting soles to uppers by a waxed thread, that the leather be drawn together as firmly as possible, in order to prevent the plates or portions of leather united by the stitches from slipping one upon the other, such movement cutting the thread and causing what is commonly called "ripping." The waxed thread in sewing is consequently subjected to all the strain 25 it will bear without breaking.

30 The large spool of waxed thread commonly used has a nut and washer, by which to adjust the tension of the thread to all it will stand.

35 In this class of sewing-machine the motion of the hooked needle as it commences to rise is much slower than at the central portion of its upward stroke. The force exerted upon the thread by the hook of the ascending needle, provided the thread extending from the whirl or work to the spool is stretched taut, 40 must be sufficient to rotate the spool or start it from a position of rest.

45 In the McKay machine the powerful tension or strain under which the thread is held during the time the machine is sewing is determined by the adjustment of friction devices connected with the spool, and the hook of the needle during sewing, by its action on the thread, turns the heavy spool with a jerk, turns it too far, as the momentum of the spool

is very considerable, and the needle then 50 draws on a loose loop, and as the slack formed by the momentum of the spool is consumed the hook of the needle again jerks the thread and again turns the spool. These jerks to overcome the inertia of the spool and the slack 55 caused by its momentum seriously impede the operation of the machine, reduce its speed, strain the needle, break the thread, and limit the speed at which the machine may be run and do good work.

60 The aim of this invention is to provide the horn with a stationary wound cop of sole-fastening waxed thread so wound thereon that the thread drawn up by the hooked needle when rising will be relieved from the variation of tension due to inertia and momentum of the usual rotating spool of thread. I employ with the said thread a tension device to act uniformly upon the thread, thereby subjecting it to equal and uniform tension during 65 the formation of each stitch, which insures a stronger seam.

70 In the McKay machine, wherein the thread is held upon a spool, as described, the maximum speed of the machine without breaking 75 the thread too much to do good work is about two hundred and fifty stitches per minute.

75 In this my improved plan, wherein the waxed thread is wound in conical layers to form a cop, from which the thread may be drawn 80 without rotating the cop, it is possible to run such machines practically at the rate of about six hundred and fifty stitches per minute, and do better work with less breakage of thread than in the old plan at the rate of two hundred and fifty stitches per minute.

85 The wax upon the wound thread, preferably like that used in hand-work, acts to hold the rounds or layers of thread together, so that such layers reel off only as drawn off positively.

90 I have also provided a novel tension device or wheel, which acts uniformly upon the thread, and which is so constructed as to permit the surplus wax left on it to escape through several small outlets therein, which prevent all liability of the wax becoming filled or baked 95 into the sharp V of the said wheel, which is

kept hot by the usual lamp, gas, or steam-jet in the horn used to keep the wax of the thread soft.

Figure 1 represents, in side elevation, a revolving horn provided with my invention and placed in operative position with relation to the usual hooked needle, such as is well known in the McKay machine. Fig. 2 is a top view of the base of the horn and the attached tension devices and thread-cop, the upper part of the horn being in section; Fig. 3, a longitudinal section taken through the tension device or wheel, and Fig. 4 an enlarged vertical and cross section of the wheel alone.

15 The revolving horn *a* will be supported and rotated as usual, and will contain the usual whirl, whirl-actuating shafts, and heating mechanism now commonly employed in the well-known McKay machine, and the hooked 20 needle *b* will be actuated as in that machine.

The waxed thread *c*, to be drawn into the soles and uppers to be united, instead of being held upon the usual headed reel turning about a vertical pivot at the center of rotation 25 of the horn, as in the present McKay machine, is placed on a bobbin, *d*, fixed upon an arm or bracket, *e*, attached to the horn, the said bobbin not rotating axially. The waxed thread is carried from the horizontally-placed 30 bobbin *d* through a guide-eye, *f*, and thence under and partially about the tension-wheel *g*, and thence upward along within the horn and through the eye in the usual whirl, from which it is taken by the hooked needle *b*. 35 This tension-wheel *g* is shown as composed of a single piece of metal grooved annularly, so as to form a sharp V-shaped recess or space, in which the thread is wedged or drawn sufficiently hard to prevent the thread moving 40 without also rotating the wheel.

The force required to rotate the wheel, and consequently the force with which the thread is held, and which has to be overcome by the pull of the needle on the thread, is regulated by 45 means of tension-controlling devices, (shown as a nut, *h*, and a spring, *i*,) which are placed on the rod *j*, that serves as the axis for the wheel *g*, the said rod *j* being squared or otherwise shaped, as at 2, to prevent it from rotating, yet permitting it to be moved in the direction of its length to release the wheel *g*, and permit it to rotate freely when required.

This longitudinal movement of the spindle or rod *j* and devices, as shown in the drawings, 55 to so move it are not herein claimed by me, as they will form the subject-matter of another application for patent made by another party.

The gas-jet or other usual heating means (not herein shown) will warm the wheel *g* sufficiently to keep soft the wax which adheres to the said wheel from the commencement to the completion of the unwinding operation, and consequently the usual difficulties experienced by the use of a rotating headed spool, 60 which, as the waxed thread was unwound from it, necessitated a constant change of tension to

compensate for the decreasing diameter of the mass of thread on the spool and its weight, are avoided, permitting the thread to be subjected in a uniform manner to all the tension it will bear without breaking. 70

By employing a bobbin of the kind described and shown to hold the waxed-thread of a sole-sewing machine, instead of the usual rotating headed spool, the speed of the machine is greatly increased. It is made to perform better work with the same material, less attention is required on the part of the operator, and time heretofore wasted by stopping to mend broken threads is saved. 75

80 The tension of the thread being uniform, it is possible to draw the stitches uniformly taut.

The bobbin upon which the waxed thread is wound is without a head at that end from which the thread is unwound, and is and may 85 be shaped as any ordinary filling-bobbin.

The essential feature of the waxed-thread-holding bobbin in this my invention is, that it shall be so shaped, held, and placed that the waxed thread may be easily drawn therefrom without rotating the bobbin, the amount of strain to draw off the waxed thread being unaffected by size or weight of the bobbin or the fact that it is more or less fully wound. 90

By reason of the shape of the base of the 95 bobbin the waxed thread may be wound as is the filling in shuttles, waxed thread so wound unwinding easier than if wound in any other shape.

The axis of the bobbin is substantially in 100 line with the guide-eye *f*, next to the tension-wheel *g*, and the thread therefore unwinds evenly from the bobbin. This waxed cop or bobbin of thread, located as described with relation to the horn and wound on a stationary bobbin, enables the thread to be more uniformly delivered than would be the case were a ball of dry thread used, the thread from the ball passing through a waxing apparatus. Dry thread cannot be thoroughly and practically waxed on the horn on its way to the 105 usual whirl and needle.

It will be observed in this my invention that the action of the tension device upon the waxed thread is constant, and that the thread 110 is not released from tension as the needle forms the loop.

I desire it to be understood that I do not broadly claim supporting the needle-thread spool upon a nearly-horizontal pin to obviate 115 rotating the said spool, and I am aware that shuttles have had their thread wound on bobbins like the bobbin employed by me.

I claim—

1. The tension-wheel provided with the V-shaped peripheral groove and with transverse outlets for the wax, the said outlets intersecting the bottom of the said groove, substantially as and for the purpose described. 125

2. The rotating horn and the tension device provided with the V-shaped peripheral groove and intersecting passages or outlets, 130

as described, for the wax at the bottom of the
said groove, combined with a bracket or bob-
bin-holder adapted to support a filling-wound
cop or bobbin of waxed thread, to permit the
5 thread to be taken off at a uniform tension
by the hooked needle for the formation of
each stitch without rotating the said cop or
bobbin.

In testimony whereof I have signed my name
to this specification in the presence of two sub- 10
scribing witnesses.

JAMES L. WITHEY.
